ALBERT A. GORDON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WARP BEAM FOR LOOMS.

Application filed December 30, 1926. Serial No. 158,065.

This invention relates to improvements in warp beams for looms and it is the general object of the invention to provide improved means for equalizing the pressure exerted by the several strands into which a warp is divided when being tied to a loom beam so that all the threads may be under the same tension.

Warp threads are usually attached to a warp beam by being grouped together and tied in one way or another to some part of the beam. It is found a matter of practical difficulty to tie all of the groups of strands under the same tension and I have devised means whereby the differing tensions of the several groups may be equalized by a flexible cord or cable held at its ends and having tied thereto at a plurality of points intermediate its ends of the several groups or strands. One form of beam for accomplishing this result is set forth in my copending application Serial No. 142,773 wherein are shown a number of hooks pivotally mounted on the interior of the beam and arranged to project through holes in the metallic shell or barrel of the beam. It is an important object of my present invention to improve upon the details of construction of the hooks and their support and also to provide convenient means for securing the flexible cable to the beam so that the same may be tightened or slackened or renewed.

It is a further object of the invention to provide means for attaching the flexible cord to a part of the beam accessible from the exterior thereof and so located as not to exert any appreciable lateral pressure on the guides for the cord.

With these and other objects which will appear as the description proceeds, my invention relates to the arrangements and combinations of parts hereinafter set forth, and more particularly pointed out in the claims.

In the accompanying drawings, wherein a convenient embodiment of my invention is shown,

Fig. 1 is a top plan view of the warp beam such as may have my invention applied thereto,

Fig. 2 is an enlarged detail vertical section on line 2—2 of Fig. 1,

Fig. 3 is a vertical section on line 3—3 of Fig. 2,

Fig. 4 is a vertical section through the beam and frictional drum therefor showing the manner of securing the flexible cord,

Fig. 5 is an end elevation looking in the direction of arrow 5, Fig. 4,

Fig. 6 is a detailed sectional view showing certain parts of the beam,

Fig. 7 is an enlarged end elevation of a portion of the structure shown in Fig. 5, and

Fig. 8 is an enlargement of a portion of Fig. 2.

Fig. 9 is a front elevation of one of the hook members.

Referring to the drawings, the warp beam comprises a hollow metallic barrel 10 having 70 adjustable false heads 11 which may be clamped to the barrel in proper longitudinal position by means of bolts 12. The barrel may have a series of aligned holes 13 for a purpose to be set forth. The present invention is not concerned with the false heads and any improved type may be employed.

As shown in Figs. 4, 5 and 6 the barrel 10 has an end thereof provided with a plurality of grooves 20 and if desired may be turned internally as at 21 to receive a hub 22 of a friction drum 23. Bolts 24 secure the hub and barrel together as shown in Fig. 4, said drum being provided with slots 25 which may be aligned with the slots 20 for the reception of said bolts. The web 26 of the drum 23 may be provided with spaced openings 27 to facilitate the assembly of the device and afford access to the bolts 24. As shown in Fig. 4 the end of the barrel 10 90 may be set accurately against the web 26 of the beam or any other portion thereof.

That portion of the beam which provides for a compensation in the uneven tensions of the various strands of warp comprises 95 a bar 30, which may be of wood if desired, secured to the interior of the hollow barrel 10 as shown more particularly in Fig. 8, by means of wood screw 31. The bar is formed with a groove 32 and may have one end 100 chamfered off as at 33. A plurality of metallic strips 34, as shown in Figs. 3 and 8, are secured to one of the sides of the strip 30 as at 35 by means of screws 36. Each of said strips shown in Fig. 3 has a body portion 37 extending along a portion of the bar 30 and has formed integral therewith a plurality of eye forming arms 38 which are

bent as shown in Fig. 8 to form a substantially closed eye 39. Said arms extends across the groove 32 and define with the same a series of pockets P into which extend 5 the ends 40 of hook members 41. Each hook member, as shown in Fig. 2, has a bent end 42 to which may be secured one or another of the warp strands W, and which may project upwardly through the holes 13 in the barrel. At a point intermediate the pivotal ends 40 and the bent end 42 I form each hook with an eye 43 which lies between adjacent arms 38.

A flexible cord or cable 50, which in this 15 instance may be made of metallic strands, extends through the eyes 39 and 43 and may be secured to the beam in the manner set forth in Fig. 4. As shown therein the friction drum 23 is recessed as at 51 to receive 20 the head of a screw or bolt 52. The end of the cable 50 is looped around the screw 52 and held tightly in place thereby as shown in Figs. 4, 5 and 7, the cable passing through one of the inner openings 27 as shown in 25 Fig. 5. By means of this construction the tension on the cable 50 may be varied and the same may also be renewed. It is desirable, though not necessary, to have the cable extend substantially parallel to the axis of 30 the beam from the last eye 39 to that part of the drum in which it is secured, as set forth in Fig. 4, this construction relieving the bar 35 and eyes of any lateral strains.

The groups of warp threads are fastened 35 to each hook one at a time, the hooks being projected through the holes 13. The cable yields so as to equalize the different tensions 40 of the several groups and all the threads are found to be under substantially the same strain.

From the foregoing it will be seen that I 45 have provided a warp beam having metallic strips secured to the interior thereof and defining with a groove formed in the carrier bar pockets to receive the ends of the hooks. It will further be seen that the cable 50 is secured to the beam near the outer part of the drum 23 so as to be readily accessible and that the point of attachment is substantially 50 in alignment with the fixed eyes through which said cable passes.

Having thus described my invention it will be apparent that changes and modifications 55 may be made therein by those skilled in the art without departing from the spirit and scope of the invention, and I do not wish to be limited to the details herein disclosed, but what I claim is:

1. In a warp beam for looms having a 60 hollow cylindrical barrel, a carrier bar secured to the interior of the barrel and having a longitudinal groove therein, guide members secured to the bar and having portions thereof extending across the groove 65 to define pockets, hook members having por-

tions projecting into the pockets to be pivoted therein, and a flexible member guided by said members and having operative engagement with the hook members, said flexible member being normally slack.

2. In a warp beam for looms having a hollow cylindrical barrel, with openings therein, a carrier bar extending along the interior of the barrel and having a longitudinal groove therein, a guide member secured 70 to the carrier bar and having portions thereof extending across the longitudinal groove in the carrier bar to form guide eyes, hook members positioned to project through the openings in the barrel and having portions to extend into the groove of the carrier bar and under the guide member, and a flexible member extending through the guide eyes and operatively connected to said hooks.

3. In a loom warp beam having a hollow 80 barrel, a carrier member extending along the interior of the barrel, a guide member fixed relatively to the barrel and having portions extending along the carrier member and provided with guide eyes, one of said members being grooved to define pockets with the other member, and hook elements having parts thereof to extend into the pockets to afford a pivotal mounting for each hook element, and a flexible member passing through 85 the guide eyes and having operative engagement with the hook elements.

4. In a loom warp beam having a hollow barrel, a carrier member extending along the interior of the barrel, a guide member 100 formed with guide eyes, hook elements having portions extending between the members for pivotal support, and a flexible member supported and guided by said guide member and operatively related to the hook elements.

5. In a loom warp beam having a hollow barrel, a head fixed to one end of the barrel, a guide member on the interior of the barrel having guide eyes, hook elements on the interior of the barrel pivotally mounted with respect thereto, and a flexible member operatively related to the hook elements and extending through the guide eyes and secured to the head at a point substantially in 115 alignment with the guide eyes.

6. In a loom warp beam having a hollow barrel, a head fixed to one end of the barrel, a guide member on the interior of the barrel having guide eyes, hook elements on the interior of the barrel pivotally mounted with respect thereto, and a flexible member operatively related to the hook elements and extending through the guide eyes and secured to the head at a point substantially the same 120 distance from the center of the barrel as the said eyes.

7. In a loom warp beam having a hollow barrel, a head fixed to one end of the barrel, a guide member on the interior of the barrel 130

having guide eyes, hook elements on the interior of the barrel pivotally mounted with respect thereto, and a flexible member operatively related to the hook elements and extending through the guide eyes and detachably secured to the exterior of the head.

8. In a loom warp beam having a hollow barrel, a head fixed to one end of the barrel, a guide member on the interior of the barrel having guide eyes, hook elements on the interior of the barrel pivotally mounted with respect thereto, and a flexible member operatively related to the hook elements and extending through the guide eyes and detachably secured to the exterior of the head in position to be disconnected while

the head is in its normal position with respect to the barrel.

9. In a loom warp beam having a hollow barrel, a head fixed to one end of the barrel, a guide member on the interior of the barrel having guide eyes, hook elements on the interior of the barrel pivotally mounted with respect thereto, and a flexible member operatively related to the hook elements and extending through the guide eyes and detachably secured to the exterior of the head at a point substantially in alignment with the guide eyes.

In testimony whereof I have hereunto affixed my signature.

ALBERT A. GORDON.
